(57) CLAIM

The ornamental design for a hair brush with color, as shown and described.

DESCRIPTION

The patent file contains at least one drawing executed in color. The Office will provide copies of this patent with color drawings upon request and payment of the necessary fee.

FIG. 1 is a perspective view of the invention;

FIG. 2 is a front elevational view of the invention, and a rear elevational view would be identical;

FIG. 3 is a left elevational view of the invention, and a right elevational view would be identical;

FIG. 4 is a top plan view of the invention; and,

FIG. 5 is a bottom plan view of the invention.

The broken lines showing a handle and bristles are included for the purpose of illustrating portions of the article that form no part of the claimed design.
